UNITED STATES PATENT OFFICE.

STERLING ELLIOTT, OF NEWTON, MASSACHUSETTS.

DESIGN FOR A SULKY FRAME OR AXLE.

SPECIFICATION forming part of Design No. 24,590, dated August 20, 1895.

Application filed November 20, 1893. Serial No. 491,495. Term of patent 14 years.

To all whom it may concern:

Be it known that I, STERLING ELLIOTT, a citizen of the United States, residing in Newton, in the county of Middlesex and State of Massachusetts, have invented and produced a new and original Design for a Sulky Frame or Axle, of which the following is a specification, reference being made to the accompanying drawing, forming a part thereof.

10 The drawing shows, in perspective, my newly-designed sulky frame or axle.

The leading feature of my design comprises a cross-piece having an arched central portion with laterally-projecting ends extending in a right line, and from each of said ends depend parallel rods.

15 Referring to the drawing, the cross-piece is

shown as having an arched central portion *a*, with horizontal lateral projecting ends *a' a'*, extending in the same right line, and depending from each horizontal projecting end are the parallel rods *b b*, separated a short distance apart.

20 What I claim is—

The design for a sulky frame or axle as 25 herein shown and described.

In testimony whereof I have signed my name to this specification in the presence of two subscribing witnesses.

STERLING ELLIOTT.

Witnesses:

FRED L. OAKS,
L. H. HOOKER.
